UNITED STATES PATENT OFFICE.

CHARLES H. FENTON, OF CHICAGO, ILLINOIS, ASSIGNOR TO THE N. K. FAIRBANK COMPANY, OF CHICAGO, ILLINOIS, A CORPORATION OF ILLINOIS.

RIVETING-MACHINE.

SPECIFICATION forming part of Letters Patent No. 785,940, dated March 28, 1905.

Application filed April 30, 1904. Serial No. 205,749.

To all whom it may concern:

Be it known that I, CHARLES H. FENTON, a citizen of the United States, residing at Chicago, in the county of Cook and State of Illinois, have invented certain new and useful Improvements in Riveting-Machines; and I do hereby declare that the following is a full, clear, and exact description thereof, reference being had to the accompanying drawings, and to the letters of reference marked thereon, which form a part of this specification.

This invention relates to improvements in riveting-machines and to an improved riveting-hammer for use in such machines; and the invention consists in the matters hereinafter set forth, and more particularly pointed out in the appended claims.

As shown in the drawings, Figure 1 is a side elevation of a riveting-machine embodying my invention. Fig. 2 is a plan view of the table and feeding mechanism. Fig. 3 is a rear elevation of the parts shown in Fig. 2. Fig. 4 is a transverse vertical section taken on line 4-4 of Fig. 2. Fig. 5 is a perspective view of the hammer. Fig. 6 is a bottom plan view thereof. Fig. 7 is an enlarged detail of the hammer. Fig. 8 is a perspective view of a pail-blank, showing the bail-ears thereon. Fig. 9 is a fragmentary section taken through a pail-wall and bail-ear, showing the ear fastened in place.

The machine herein shown has been designed more especially for attaching to the flat sheet-metal blank of a pail-wall before the blank is formed to constitute the pail the bail-ears by which the bail is loosely connected or hinged to the pail, of such a construction, for instance, as is shown in the pending application of Frederick H. Brennan, Serial No. 173,945, filed September 21, 1903, but may be adapted for other riveting-work.

The form of bail-ear shown in the aforesaid application and the manner of attaching the same to the wall of the pail are shown more clearly in Fig. 9. Said bail-ear A consists of an oblong hollow or cup-shaped part, preferably made of sheet metal and arranged at its open side to fit in a depression b in the wall B of the pail, and the ear is attached to said

pail-wall by means of a rivet A', extending 50 through the wall of the pail and the outer wall or side of the bail-ear. Said bail-ear is provided with an aperture a to receive the bail. Both bail-ears of a pail are attached to the blank from which the pail is afterward 55 formed while the blank is spread flat, the headed rivets being passed upwardly through the blank and bail-ear and extending a distance above the ear. The extended part a' of the rivet is thereafter upset or clenched down 60 over the bail-ear. Inasmuch as that portion of the rivet in the space between the pail-wall and the outer side of the bail-ear is unsupported at its sides difficulty has heretofore been experienced in properly riveting or 65 upsetting the end a' of the rivet without effecting a contraction or shortening of the rivet or a lateral bending thereof to an objectionable extent, or, more specifically, if the rivet be made of sufficiently soft material to 70 enable the end to be readily upset or clenched it is likely to be bent or shortened in the manner described, and if made sufficiently hard to resist such shortening or bending tendency it is so hard as to prevent the same 75 from being readily clenched in place. The machine herein illustrated has been devised to upset said rivet and at the same time avoid the objections heretofore noted.

One of the principal features of the machine 80 herein shown, by which these difficulties are overcome, consists in providing the riveting-face of the riveting-hammer with a plurality of closely-spaced projections or teeth, which act, when the hammer strikes the rivet, to 85 mutilate the end of the rivet in such manner that the rivet may be readily upset or spread to form the proper-shape finished head. Said teeth may be formed by scoring the riveting-face of the hammer in a crisscross manner, 90 as shown in Fig. 6. In the organized machine the hammer and work are relatively movable during the riveting operation, so that said teeth or projections of the hammer at different blows thereof strike the rivet at different places, so that said teeth have the effect to mutilate and spread the end of the rivet outwardly over the face of the ear or 95

other part which is being riveted. Desirably the hammer is made of oblong shape, and the work is carried beneath the hammer through the medium of a suitable feeding mechanism, 5 and the hammer strikes the rivet a number of times while the work is passing thereunder, so as to insure the proper spreading and clenching of the rivet. If the work is of such nature as to require a finished appearance, the 10 oblong hammer is preferably provided at its end which last strikes the rivet with a plain face, which has an effect in striking the rivet one or more times to smooth or give finish to the upset head. The riveting-face of the hammer is made tapering, being made gradually deeper from the end which first strikes the rivet toward its other end, so that as the rivet is shortened by reason of the clenching or 15 upsetting operation the hammer, which usually has a definite length of stroke, strikes the rivet with uniform force at each blow.

Referring now to the structural details of the machine herein illustrated for effecting the clenching operation in accordance with 20 the mode hereinabove briefly outlined, the said machine is made as follows:

C designates a press-stand upon which the operative parts of the machine are supported and which may be made of any suitable form 25 or shape. Attached to said stand is a bracket D, consisting of a horizontal table D', a vertical web or plate D'', by which the bracket is attached to the front face of the stand through the medium of bolts or screws d, and 30 a triangular brace D'.

E E' designate upper and lower feed-rollers, one pair located at each side of the table D', with their lines of contact substantially in the plane of the upper face of the table. 35 The shafts of said rollers are mounted in bearing-blocks E' E'', which latter are located in vertical guides or ways in bearing-brackets D', extending upwardly from the table D' at the corners thereof. The upper rollers are 40 pressed toward the lower rollers to insure proper feeding engagement by means of springs e, that are interposed between the caps of said bearing-brackets and the upper bearing-boxes. The shaft of one of the rollers is provided with a pulley E³, which is 45 adapted to be driven by a belt directed from an overhead shaft. E⁶ designates a second pulley fixed to the same shaft, and the corresponding shaft at the other side of the table 50 is provided with a like pulley E⁷. Motion is transmitted from the pulley E⁶ to the pulley E⁷ through the medium of a belt E⁸, Fig. 1. The rollers of each pair are geared together 55 at the ends thereof remote from the belt-pulleys by means of gear-wheels E⁹ E⁹, whereby the feed-rollers are driven at equal peripheral speed.

D⁵ designates a bed-plate or anvil, which is located in a suitable depression in the table 60 and made of metal harder than the table, and

said anvil D⁵ coöperates with the hammer F, hereinafter to be described, in effecting the proper riveting operation, said plate serving as an abutment against which said hammer acts in the riveting or clenching operation. 70 Said anvil D⁵ extends a distance beyond the advance feed-rolls of the machine, or that which first receives the blank B, and is supported at its extended end upon an extension-table D⁶ of any suitable construction, the upper face of which extension-table is located at the plane of the upper face of the anvil. 75

The hammer F is shown in detail in Figs. 5, 6, and 7 and consists of a flat riveting portion f and a central rib f' on the side remote from the riveting-face by which it is attached to the actuating mechanism, giving to the entire tool a T-shape cross-section. The hammer is attached in any suitable manner to a reciprocating plunger G, which slides vertically in suitable guides g of the press-stand. As herein shown, the lower end of said plunger is provided with a groove which receives the rib f' of the hammer. The upper end of said reciprocating plunger is loosely connected with or hinged to a pitman C', which is connected at its upper end with the crank C² of a horizontal shaft C³, which is mounted in upwardly-extending arms C⁴ of the press-stand. Said shaft is provided with a driving-pulley c and with a fly-wheel c². The hammer is located vertically over and is parallel with the bed-plate and is made of a length but slightly less than the distance between the feeding-rollers E E', as herein shown. The 100 riveting-face of the hammer consists of two principal portions f² f³, as herein shown, the former being made roughened to constitute teeth or projections (shown enlarged in Fig. 6) and the latter being made plain to constitute a finishing-surface. The riveting-face of said tool is made inclined, it being made shallower at its end which first has contact with the rivet than at the other or finishing end thereof. The actuating mechanism for the tool described is such that the length of blows imparted to the tool are uniform or equal, and the taper given to the face of the tool is such that the force of the blows on the rivet are uniform, notwithstanding the shortening 105 of the rivet at each blow.

The blank or sheet of tin from which a pail is to be formed, with the two bail-ears fitted in the depressions therein and the rivets extending upwardly through the blank and ears, 110 as shown in Figs. 8 and 9, is fed endwise from the table D⁶ to the feed-rolls and is by said rolls advanced over the table D' with one ear in advance of the other, and the parts of the sheet to which the ears and rivets are attached 115 are located over the anvil and beneath the hammer, so that said anvil shall resist the blows of the riveting-hammer. The feed-rollers are provided with grooves or cut-away portions e', made of sufficient depth to permit 120

the bail-ears and depressions in the blank which receive the ears to pass therethrough in the travel of the sheet or blank. The table D' is provided with gage-bars D⁷, by which 5 the sheet is guided through the machine, and said gage-bars are fixed to the table by means of bolts d' d² extending through the bars and short transverse slots in the table. Said slots enable the gage-bars to be adjusted to sheets 10 or blanks of varying widths.

In order to hold the ears in place before the riveting operation has begun, a guide H is located over the anvil, beneath which the ears pass. Said guide is supported above the anvil by means of arms H' H² H², the former attached to the edge of the extension of the anvil and to which the guide is affixed and the latter attached to the table D' by means of the bolts d', by which one of the gage-bars is held 15 in place. The guide is preferably made of wire and is affixed to said arms in any suitable manner. The guide H is located a distance inside the margin of the anvil in the extended portion of said anvil, but is offset outwardly after it passes beneath the feed-roller (the guide passing between the rollers at the grooves e') to bring the guide out of the path 20 of the hammer.

The operation of the machine will be obvious from the foregoing, but may be briefly recapitulated as follows: The blank B is laid on the extension-table with the recesses b upward and the ears fitted therein and with the rivets A' extending upwardly therethrough. 30 Thereafter the blank is fed between the feed-rolls, with the ears over the extension of the anvil and beneath the guide H. The feed-rolls carry the blank forwardly, and after the ears pass the first pair of feed-rolls the rivets are brought under the influence of the hammer, which is rapidly reciprocated by its actuating mechanism. As the work is fed beneath the hammer the rivet is struck a number of times, depending upon the speed of advance 35 movement of the blank B and the speed of reciprocation of the hammer. The teeth or projections of the hammer upset or clench the rivet in the manner described by its repeated blows, and the clenched end of the rivet 40 is finished or smoothed by the plain part of the hammer-face. The mode of feeding the blank to the hammer brings one rivet under the hammer at a time, the blank advancing after one rivet has been clenched, so as to pass 45 the other ear and rivet thereunder to fasten the last-mentioned ear in place. The distance between the two pairs of rollers at the opposite sides of the machine is such that the advance margin of the blank will be gripped by 50 the pair of rollers at the rear side of the table before the rollers at the front side thereof release the rear margins of said blank, thus insuring an automatically-continuous movement 55 of the blank through the machine.

60 The machine herein shown or modifications

thereof may obviously be employed for riveting together other parts, and the structural details thereof may be correspondingly changed. In some instances, as where the rivet is laterally supported or closely surrounded throughout its length, the roughening of the hammer-face may be omitted and the entire face made plain. The adaptation of the machine to the work herein referred to has been explained to enable the operation of the machine to be 75 clearly understood.

I claim as my invention—

1. A riveting-machine comprising an anvil, a hammer located above the anvil and means for rapidly reciprocating said hammer toward 80 and from the anvil, said anvil and hammer having flat opposing faces and constructed and arranged to permit the work to be advanced between the same between the successive blows of the hammer, the opposing faces 85 of the hammer and anvil being relatively inclined in such manner that the face of the hammer at the receiving end of the machine is located farthest from the anvil and gradually approaches the anvil toward the discharge 90 end of the machine, whereby the successive blows delivered by the hammer to the rivet as the work is advanced beneath the hammer are of substantially equal force notwithstanding the shortening of the rivet. 95

2. A riveting-machine comprising an anvil, an oblong hammer, means for giving motion to the hammer and means for feeding the work beneath the hammer, said hammer having an inclined riveting-face, it being spaced 100 farther from the anvil at its front than at its rear end, whereby the successive blows delivered by the hammer to the rivet as the work is advanced beneath the hammer, are substantially of equal force notwithstanding the shortening 105 of the rivet.

3. A riveting-machine comprising an anvil, an oblong hammer beneath which the work is designed to be advanced between the successive blows of the hammer and means for giving motion to the hammer, said hammer having a riveting-face which is longitudinally inclined relatively to the upper face of the anvil, the advance end of the face being farthest from the anvil and formed with a series 110 of closely-spaced teeth or projections, and the rear end of said hammer-face being made plain, whereby the successive blows delivered by the hammer to the rivet, as the work is advanced beneath the hammer, are substantially 115 of equal force notwithstanding the shortening of the rivet.

4. A riveting-machine comprising an oblong anvil, an oblong hammer, means for giving motion to said hammer constructed to impart 125 to the hammer, as a whole, strokes always of equal length, said hammer having an inclined riveting-face, it being spaced farther from the anvil at its end thereof which first strikes the rivet than at its other end, the advance 130

portion of the face being provided with a plurality of closely-spaced teeth or projections and the other part being made plain, and means for advancing the work beneath said hammer.

5. A riveting-machine comprising an oblong anvil, an oblong hammer, means for giving motion to said hammer, and front and rear pairs of feed-rollers for advancing the work over the anvil beneath the hammer, said hammer being provided with a riveting-face that is inclined to the anvil, the advance portion of said riveting-face being provided with teeth or projections and spaced farthest from the anvil and the remaining portion of said face being made plain.

10. A riveting-machine comprising an oblong anvil, an oblong hammer, and means for giving motion to said hammer, front and rear pairs of feed-rollers, said rollers being provided with registering annular grooves to per-

mit a thickened part of the work to pass therethrough.

15. A riveting-machine comprising an oblong anvil, an oblong hammer, means for giving motion to said hammer, front and rear pairs of feed-rollers, said rollers being provided with registering annular grooves to permit a thickened part of the work to pass therethrough, and a guide located above and extending longitudinally of the anvil and adapted to engage the upper face of the work, said guide extending through the registering grooves of the feed-rollers.

20. In testimony that I claim the foregoing as my invention I affix my signature, in presence of two witnesses, this 25th day of April, A. D. 1904.

CHARLES H. FENTON.
